(57) CLAIM

The ornamental design for a tooth fairy pillow, as shown and described.

DESCRIPTION

FIG. 1 is a top view of the tooth fairy pillow embodying my new design;

FIG. 2 is a front view thereof;

FIG. 3 is a right side view thereof;

FIG. 4 is a bottom view thereof;

FIG. 5 is a rear view thereof; and,

FIG. 6 is a perspective view thereof.

The broken lines showing lace on the outside perimeter of the tooth fairy pillow and of the tooth are shown for illustrative purposes only and form no part of the claim. The dotted lines on the perimeter of the tooth fairy pillow and on the pocket represent conventional stitching.
